CLAIM

We claim the ornamental design for a gaming machine, as shown and described.

DESCRIPTION

FIG. 1 is a front perspective view of a gaming machine showing my new design.

FIG. 2 is a front view of the gaming machine shown in FIG. 1.

FIG. 3 is a rear side view of the gaming machine shown in FIG. 1.

FIG. 4 is a left side view of the gaming machine shown in FIG. 1.

FIG. 5 is a right side view of the gaming machine shown in FIG. 1.

FIG. 6 is a top view of the gaming machines shown in FIG. 1; and,

FIG. 7 is a bottom view of the gaming machine shown in FIG. 1.

The broken lines in the drawings are for the purpose of illustrating environmental structure which form no part of the claimed design.

1 Claim, 7 Drawing Sheets

Related U.S. Application Data

continuation of application No. 29/631,037, filed on Dec. 27, 2017, now Pat. No. Des. 843,482.
